UNITED STATES PATENT OFFICE.

CLIFFORD H. FULLER, OF CHICAGO, ILLINOIS.

NONFREEZING UNIT FOR AUTOMOBILES.

Application filed December 9, 1926. Serial No. 153,543.

My invention relates to the cooling systems of internal combustion engines, and more particularly to a device for preventing the water contained in such systems from freezing.

In operating a motor vehicle during cold weather, it is a well known fact that the motor does not function efficiently until its internal temperature has reached a certain point, also that if the vehicle is allowed to stand for any great length of time during freezing weather, the water in the radiator and water jacket will freeze and cause considerable trouble.

15 The principal object of my invention is to provide a device whereby the water from the cooling system may be automatically drained therefrom when the motor ceases to function and be stored in a compartment which is so 20 designed as to conserve the heat contained in the water and thus prevent its freezing.

A further object of my invention is to so construct the device that it may be used when desired and disconnected from the 25 cooling system at other times, as it is evident that such a device is unnecessary during warm weather.

A still further object of my invention is to provide a device which may be readily 30 installed on any motor vehicle without making extensive alterations thereto, which will be fully automatic in operation, and which will require little or no attention.

These, and various other objects and 35 advantages, will be more clearly understood from the following description and from the accompanying drawings in which:

Fig. 1 is a fragmentary side view of an automobile, certain parts having been broken away in order to show my invention installed 40 thereon.

Fig. 2, a cross-sectional view of a preferred embodiment of my invention, taken on line 2—2 on Fig. 1 and drawn to a larger 45 scale, and

Fig. 3, a fragmentary view, taken approximately on line 3—3 on Fig. 2, showing a method of securing the insulating material.

Referring now more in detail to the drawings, 5 represents an automobile having a motor 6 and a radiator 7. A water jacket 8 surrounds and forms a part of motor 6 and is provided with an outlet and inlet whereby it may be connected to the radiator in the usual manner.

55 My device consists primarily of a tank 9,

a pump 10, a feed conduit 11, connecting pump 10 to water jacket 8, a return conduit 12, connecting the bottom of radiator 7 to tank 9, an overflow conduit 13, and a drain 14.

The tank 9 has an inner shell which is preferably made of copper or other ductile material and is cylindrical in shape with a flat top 15 and a downwardly and inwardly sloping bottom 16. The top 15 has an aperture 17 surrounded by a flange 18 which extends upwardly and is preferably integral with the top 15. I have shown the inner shell as having the side and bottom walls 70 integral and the top 15 flanged to fit over the top of the side walls. The inner shell may be made in any suitable manner, it being understood that all seams or joints are suitably brazed or soldered so as to form an 75 air-tight structure. The bottom wall 16 is provided at its center with an aperture into which drain 14 is soldered or brazed, thus forming a tight tank, with the exception of aperture 17, which is closed in a manner to 80 be later described.

The inner shell is entirely covered with a layer of wool felt, or other suitable heat insulating material, which is held in place by means of a series of straps 19 extending 85 radially from the flange 18 across the top, down the sides, and radially inward across the bottom to a point adjacent the drain 14. The upper ends of the straps 19 are held in place by a ring 20, which encircles the flange 18, and the lower ends by a ring 21, which encircles the drain 14. A wooden ring 22 is placed on the ring 20 and an internally threaded bushing 23 inserted inside the flange 18 and brazed in place. The bushing 90 23 has a horizontally extending flange 24 which engages the top of ring 22 and holds same securely in place, together with the ring 20 and the ends of straps 19.

A series of wooden blocks 25, cut to form a circle, are placed against ring 21 and a series of other blocks 26 are placed against the straps 19 at spaced intervals around the bottom of the tank. A series of wooden hoops 27 are placed around the shell so as to hold the straps 19 and the insulating material thereunder firmly in place and a series of blocks 28 placed against the straps on the top of the shell. An outer shell 29, made of sheet metal, surrounds the wooden blocks and hoops and is soldered to drain 14 and to flange 24 so that a chamber is formed be-

tween the outer and inner shells, from which the air may be partially exhausted.

A bushing 30, preferably of cast metal, is threaded into bushing 23 with its flange 5 overlapping flange 24; between which a gasket 31 is placed in order to provide a tight joint. Bushing 30 is provided with an aperture 32 through which the contents of the tank may be inspected or measured and which is closed by means of a suitable cap 33. Bushing 30 is also provided with an aperture 11^a, through which conduit 11 is threaded, and an aperture 13^a to receive the end of conduit 13. A pump shaft 34, adapted to actuate pump 10, extends through a stuffing box 35 located in the center of the bushing 30.

The lower end of feed line 11 depends into tank 9 to a point near its bottom where it 20 is connected to pump 10, a short distance above which a check valve 36 is let into the conduit. A drain hole 37 is located in the conduit just above valve 36. The other end of feed line 11 is threaded into the bottom of 25 water jacket 8 and is provided with a valve 38 for governing the flow of water from the pump to the water jacket.

The other end of conduit 13 is connected into a special fitting located in the regular 30 connection between the top of the radiator and the top of the water jacket. The function of this line is to return water to the tank 9 in case water is pumped through feed conduit 11 faster than it can flow through the 35 radiator.

Return line 12 has one end connected to the bottom of the radiator and the other end to the side of tank 9 in any suitable manner. A valve 39 is located in the return line 12 40 for the purpose of regulating the flow of water from the radiator to the tank, so that the radiator will always remain full of water. This line is preferably insulated its entire length. A branch 40 connects line 12 45 with the water jacket and is provided with a valve 41 so that water may be allowed to flow through the branch when so desired, but it is understood that this valve is closed when the device is in use.

Pump 10 may be actuated by mechanically connecting shaft 34 with an electric motor suitably mounted near the tank, as shown 50 in Fig. 1, or by mechanically connecting it to a shaft 42, as shown in Fig. 2, which in 55 turn is mechanically connected to a moving part of the motor, such as the crankshaft or fan pulley. If operated by a motor, the circuit for furnishing electric current thereto is controlled by a switch which may be 60 operated independently of or concurrently with the ignition switch.

In installing the device on a motor vehicle, a tank is provided which will hold approximately two gallons more water than the 65 water cooling system to which it is attached.

It being understood that the water in the tank should not rise above the end of return conduit 12, as it is evident that a higher level would fill this conduit for a considerable distance and thus be more liable to 70 freeze, due to the small cross-sectional area of the pipe, than would the water in tank 9. The tank may be filled by pouring the water through opening 32 or through the filler pipe on the radiator.

After the device has been installed and filled with water, the motor may be started in the usual manner, which will cause pump 10 to operate and pump water into the water jacket of the motor through conduit 11. After the water enters the water jacket, it rises, due to both the heat of the engine and to the action of the pump, and passes from the top of the water jacket into the top of the radiator where it is cooled and travels toward the bottom of the radiator from whence it is carried by return conduit 12 back into tank 9.

As soon as the water is in circulation valve 38 is adjusted to regulate the velocity with 90 which the water is furnished to the motor and then valve 39 is regulated to slightly retard the return flow in order that the water in the radiator may be kept at the proper level. From this point on, no attention to 95 the device is required, with the exception of occasionally adding to the water as is usual in the operation of motor vehicles.

When the motor is stopped, the water in the radiator will drain back through conduit 12, the water in the water jacket will drain back through conduit 11 and drain hole 37, so that it is all contained in the tank 9 and thus protected against freezing when the vehicle is standing idle.

It is evident that with such a device installed on a motor vehicle, the use of alcohol, glycerine or other non-freezing mixtures is entirely unnecessary and that the motor will function more efficiently due to the heat 100 imparted from the water.

After the cold weather has passed, or at any other time when it is desired to discontinue the use of the device, valves 38 and 39 are closed and valve 41 opened. If the 115 pump is motor driven, the switch controlling such motor is left permanently open, or if the pump is driven by means of the crankshaft or fan pulley, the mechanical connections are moved out of connection therewith, so that the pump will not function. After the device has been thus disconnected, the circulation of the water in the cooling system will operate in the same manner as though the device had never been 120 installed.

The branch 40 and conduit 11 have been shown as entering opposite ends of the water jacket, but it is understood that these pipes may be connected at any suitable

point, both being preferably connected at the rear lower end of the water jacket.

While I have illustrated and described an embodiment of my invention and the manner in which it may be put into practical use, it will be readily understood that various modifications and applications may be made without departing from the spirit of the invention, and hence, I do not wish to limit myself to the precise embodiment set forth, but consider that I am at liberty to make such changes and alterations as fairly come within the scope of the appended claims.

Having thus described my invention, what I claim as new and desire to protect by Letters Patent is—

1. A device of the class described including a tank having an opening in its top and a drain in its bottom, a layer of heat insulating material surrounding the tank, a sheath surrounding the insulating material and connected to the edges of the opening, and to the drain, a bushing in the opening,

a pipe depending through the bushing, a pump on the pipe, means extending through the bushing for operating the pump, a conduit adapted to connect the pump pipe with the cooling system of an internal combustion engine, and a return conduit adapted to connect the said cooling system with the tank.

2. In combination with an internal combustion engine having a water jacket and a radiator, a tank for holding water, a layer of heat insulating material around the tank, a protecting sheath enclosing the insulating material, a feed conduit between the water jacket and the tank, a pump connected to the feed conduit, a return conduit between the radiator and the tank, valves in both conduits adapted to regulate the flow of water therethrough, a branch between the return conduit and the water jacket, a valve in the branch, and means to actuate the pump.

In testimony whereof I have signed my name to this specification.

CLIFFORD H. FULLER.
